POWER-DRIVEN MECHANISM FOR OPERATING TYPE BARS AND OTHER INSTRUMENTALITIES OF TYPEWRITERS OR LIKE MACHINES

Henry J. Hart, West Hartford, Conn., assignor to Royal Typewriter Company, Inc., New York, N. Y., a corporation of New York

Application July 1, 1949, Serial No. 102,634

10 Claims. (Cl. 197—17)

1 This invention relates to power driven mechanism for operating type bars and other instrumentalities of typewriter or like machines.

In one of its aspects the invention relates more particularly to an improved mechanism for transmitting drive from a constant speed motor to a continuously driven rotary driving member embodying a novel and effective device for varying the rotative speed of the driver so as to vary the operating effort delivered to the type bars or other instrumentalities.

One object of the invention is to provide mechanism for varying the speed of a driver of the kind referred to above, including a V-type groove pulley having sections divided from each other medially and being relatively shiftable or displaceable axially so as to vary the width of the pulley groove and hence the effective diameter at which a cooperating belt engages the pulley.

In another of its aspects the invention relates more particularly to improvements in power generating or transmitting mechanism of the kind disclosed in the copending application of William H. Kupper, Serial No. 6,066, filed February 3, 1948, now Patent No. 2,567,945, dated September 18, 1951. The mechanism disclosed in the copending application includes a driving member in the form of a continuously rotating snatch roll adapted to transmit drive to a typewriter instrumentality through a toothed driven element adapted to be moved, under key control, into a snatch roll tooth interspace. Improvements similar to those disclosed in the present application as being embodied in type bar operating mechanism are disclosed and claimed generally in the copending application of Henry J. Hart, Serial No. 98,738, filed June 13, 1949, now Patent No. 2,563,722, dated August 7, 1951, in which the improvements also are claimed as being embodied in escapement operating mechanism.

Another object of the present invention is to provide a new and improved arrangement for varying or adjusting the amount of driving effort imposed upon or transmitted to a typing member by a continuously rotating toothed snatch roll.

Another object of the invention is to provide adjusting or drive-effort-varying means of the kind referred to, by which the adjustment is effected by variably limiting the extent to which a toothed driven element is moved into a tooth interspace on a rotating snatch roll.

Another object of the invention is to provide a belt and pulley drive mechanism for a power-operated typewriter or like machine including a novel and improved belt tensioning device.

2

Other objects of the invention will become apparent from a reading of the following description of a preferred embodiment of the invention, the appended claims, and the accompanying drawings in which:

Figure 1 is a view, partly in elevation and partly in vertical section, fore-and-aft of a typewriter embodying the invention, showing only some of the conventional or standard typewriter parts in order to illustrate the application of mechanism embodying the invention to a typewriter construction;

Figure 2 is a detail perspective view of a pulley section and associated parts shown in separated relation;

Figure 3 is a fragmentary vertical sectional view on the line 3—3 of Figure 1, drawn on an enlarged scale;

Figure 4 is a fragmentary view showing parts in section on the line 4—4 of Figure 3 and showing a portion of an associated typewriter frame or mask side wall;

Figure 5 is a developed view of an adjusting knob, showing an associated part of a frame wall in horizontal section;

Figure 6 is a vertical section taken end-to-end of the machine on the irregular line 6—6 of Figure 1;

Figure 7 is a detail perspective view of a portion of a preferred form of flexible belt;

Figure 8 is a horizontal sectional view on the line 8—8 of Figure 1, showing an idler pulley belt tensioning device; and

Figure 9 is a fragmentary fore-and-aft sectional view of a type bar operating mechanism, some parts being shown in elevation.

The invention may be embodied in typewriters or like machines of various kinds. For the purposes of illustration, the invention is shown as being embodied in an office type typewriter having, except for the power mechanism to be described, many features in common with the well known Royal Standard typewriter. The drawings show only enough of the standard or known typewriter construction to assist in illustrating the manner in which mechanism embodying the invention may be coordinated with other parts of a typewriter construction.

The known construction illustrated includes a main frame A on which a carriage B equipped with a platen C is mounted for letter spacing and return movements by means of a top rail 1 secured to the carriage, and rolling upon balls 2, which in turn are adapted to roll on a frame-mounted bottom rail or track 3.

3

The carriage may be driven toward the left, that is, in the letter-spacing direction, by any suitable mechanism, for example, by a spring barrel and draw band of known or suitable construction (not shown), under the control of suitable escapement mechanism operated, for example, as disclosed in the aforementioned copending application of Henry J. Hart, Serial No. 98,738, filed June 13, 1949.

Returning of the carriage toward the right may be effected by power controlled from the typewriter keyboard, for example, by mechanism of the kind disclosed in the copending application of Henry J. Hart, Serial No. 21,476, filed April 16, 1948, now Patent No. 2,567,937, dated September 18, 1951.

The machine is provided with the usual complement of type bars, one of which is shown at 4 in Figures 1 and 9 as being pivoted at 5 on a support or segment 6 equipped with a type bar abutment or banking ring 7. Normally the type bar 4 is in the position shown in Figure 1 with the type head resting upon a cushion 8. The invention will be described in connection with the operation of type bars or other typing members, but it will be understood that features of the invention may be utilized in the operation of other typewriter or like machine instrumentalities.

Power for operating the type bars or other instrumentalities is supplied by an electric motor D, and is transmitted through a mechanism train or connections generally designated E to an actuating mechanism generally designated F. The mechanism F is generally similar to mechanism described and claimed in copending application Serial No. 98,738 referred to above, and is similar to but embodies improvements in mechanism disclosed in the aforementioned copending application of William H. Kupper, Serial No. 6,066, filed February 3, 1948. It includes a continuously operating driving element and controllable driving connections, which normally are inoperative or ineffective, but which may be conditioned by the operator to effect operative driving connection between the continuously moving driving member and the train of connections E. The driver is constituted by a continuously rotating element, more particularly a toothed snatch roll or bar 9, which may be of known form, and which is adapted to be driven in the direction of the arrow a in Figures 1 and 9 by the electric motor D.

The mechanism for transmitting drive from the driver 9 to each of the type bars 4 includes an actuator 10 which extends fore-and-aft of the typewriter and above the member 9. The actuator 10 is pivoted as at 11 to a lever 12 at a point off-set relatively to the pivotal mounting 13 of the lever on a fixed frame cross bar 14. The actuator has a forwardly extending part 15 projecting under an abutment or guide plate 16 mounted by screws 17 on the frame A to extend parallel to the snatch roll 9. A spring 18, interposed between the front end of the actuator 10 and the frame A at a point not shown, yieldably urges the actuator to rock clockwise, and thus normally maintains the actuator in the position shown in Figures 1 and 9 with its front end part 15 bearing against the abutment or guide plate 16. Another abutment 19 is disposed below the abutment 16.

A link 20, pivotally connected to the lever 12 and the heel of the type bar 4 at 21 and 22 respectively, causes the type bar to be driven clock-

4

wise to printing position when the lever 12 is rocked counterclockwise in the manner described below.

In order to apply a power impulse to the type bar 4, the actuator 10 is operatively but indirectly connected to the driving member 9, the actuator itself never engaging the driving member. Mechanism for bringing about the operative connection of the actuator element 10 to the member 9 includes an interponent pawl 23, pivoted as at 24 on the actuator. A spring 25, anchored to the actuator 10 and connected to the pawl 23, biases or urges the latter to rock clockwise so as to move its nose 23a into engagement with the snatch roll 9. Normally, the pawl is maintained out of engagement with the snatch roll by the restraining action of a control element or trigger 26 which is pivoted as at 27 on the actuator 10. In the normal position of the trigger, its rear end 28 engages a holding surface 29 on the pawl so as to prevent the spring 25 from rocking the pawl element 23 into transient drive-transmitting engagement or connection with the driving member 9. The pawl 23 is formed with an inclined resetter cam face 30 which is located just below the holding surface 29, and which is acted upon by the trigger for rocking the pawl counterclockwise, and thus resetting it in normal, inoperative position.

Operator controlled means including a manually operable key 31 pivoted at 32 on the frame A is provided for bringing about operative driving connection between the driver 9 and the actuator 10. The key 31 has an upward projection 33 disposed behind an arm 34 of an operating lever 35, pivoted as at 36 on a frame-mounted cross bar 37. The lever 35 has another arm 38 on which a limber dog or flipper 39 is pivoted at 40. A spring 41 urges the limber dog 39 to rock clockwise to yieldably retain it in its normal position of rest against a limit stop 42. The dog 39 can swing counterclockwise from the position shown in Figures 1 and 9, but cannot move clockwise from this position. A returning spring 43, interposed between the key 31 and a short arm 44 on the lever 35, yieldably holds the lever 35 and the key 31 in their normal positions. In the normal positions of the parts, the lower end of the limber dog 39 overlies a contact ear 44 on the actuator 10.

In operation, when the key 31 is depressed, the lever 35 is rocked clockwise to cause the flipper 39 to push the actuator 10 downwardly to an initial extent sufficient to bring the trigger 26 into engagement with the abutment 19. This causes the trigger to be rocked clockwise about its pivot 27, so as to release the pawl 23, which is then moved by the spring 25 into engagement with the snatch roll 9. The snatch roll then drives the pawl 23 and actuator 10 as a unit so as to rock the lever 12 and operate the link 20 and type bar 4. When the pawl 23 is cast off from engagement with the snatch roll 9, the spring 18 lifts the actuator 10 to bring the trigger 26 into engagement with the upper, trigger-resetting abutment 16. This causes the trigger 26 to be rocked counterclockwise, so as to move its end 28 against the resetting cam face 30 of the pawl 23, thereby restoring the latter to its inactive position. The parts of the mechanism F will then be returned to their normal positions by a spring (not shown) but which may be interposed between a part at the rear of the frame A and a link 45 connected to the lever 12.

Means are provided for adjusting or varying the amount of driving impulse delivered to the individual pawl 23 by the snatch roll 9. In accordance with the invention, the individual variation or adjustment is effected by variably limiting the extent to which the actuator pawl nose 23^a enters a tooth interspace on the snatch roll 9 under the urge of the spring 25 when the restraint of the trigger 26 on the pawl 23 is discontinued. In the form shown, the actuator 10 is provided with a downwardly extending stop element or finger 46 which is disposed in front of and normally out of contact with a downwardly extending stop part, heel, or finger 47 on the pawl 23. When the pawl 23 is rocked clockwise by the spring 25 so as to move the pawl nose 23^a into a snatch roll tooth interspace, the pawl stop 47 moves toward the actuator stop 46, which may be so positioned as to be engaged by the stop 47 to arrest rocking of the pawl 23 before the tooth 23^a moves to the root of the snatch roll tooth interspace. By variably positioning one of the stops 46, 47, e. g., by bending the stop 46 towards or away from the stop 47, the extent to which the pawl tooth 23^a enters the tooth interspace can be varied. Consequently, the angle through which the snatch roll rotates while in contact with the pawl, which determines the amount of driving of the pawl 23 and the actuator 10 by the snatch roll 9, can be varied. Any suitable means or construction may be provided for adjusting one of the stops 46, 47 relatively to the other. In the preferred construction the stop 46 is formed integrally with the actuator 10 so as to be bendable toward or away from the stop 47. Thus, when the finger 46 is bent to the position indicated in dotted lines at 46^a in Figure 9, it will be contacted by the stop part 47 on the pawl 23 when the pawl nose 23^a has entered a tooth interspace to a relatively small extent. The resultant driving of the pawl 23 and actuator 10 by the snatch roll 9 accordingly will be of relatively short duration. On the other hand, if the actuator finger 46 is bent to the position shown in dotted lines at 46^b in Figure 9, the pawl tooth 23^a will be permitted to make a relatively deep entrance into a tooth interspace, and the driving of the pawl and actuator accordingly will be relatively greater.

In typewriters or like machines in which all or some of the instrumentalities to be operated, e. g., escapement mechanism, carriage return mechanism, tabulating mechanism, as well as typing mechanism, are operated by power, it is desirable to provide means for varying collectively the driving impulse transmitted to the several actuator pawls corresponding to the pawl 23 and associated with the other type bars and mechanisms referred to. In accordance with a further feature of the invention, new and improved mechanism is provided for varying the rotative speed of the snatch roll 9 so as consequently to vary the intensity of the impulses transmitted to the actuator pawls. The electric motor D preferably is of a kind to operate at a substantially constant speed, and the variation of the snatch roll speed is accomplished by means of variable ratio drive mechanism embodied in the transmission train E interposed between the constant speed motor D and the actuating mechanism F.

As shown in Figure 6, the motor D is mounted on the frame base by means including a bracket 48 through which the motor shaft 49 extends. Secured to the shaft 49 is a small pulley 50 which

drives a belt 51 trained around a larger pulley 52 the hub 53 of which is fitted with a bearing liner or bushing 54 journaled on a stub axle 55 secured to a standard 56. The standard 56 may be formed with an oil passage 57.

The portion of the pulley hub 53 extending to the right of the pulley 52 is formed as another small pulley 58 which is engaged by a belt 59 trained around a larger pulley 60 keyed to a shaft 61. The shaft 61 is rotatably mounted by a bearing 62 carried by the standard 56 and a bearing 63 on another standard part 64. The bearings 62 and 63 may be lubricated through oil passages 65. The standards 56 and 64 may be formed in one piece, secured to the frame base by screws 66.

Secured to the outer or right-hand end of the shaft 61 by means of a set screw 66 is a V-type groove pulley 67 which is driven at a substantially constant speed by the motor D through the pulleys 50, 52, 58 and 60, the belts 51 and 59, and the shaft 61. An antifriction thrust bearing 61^a is interposed between the pulley 67 and the standard 64. A V-type belt 68 is trained around the constant speed pulley 67 and another V-type groove pulley generally designated 69 connected to the snatch roll 9. The belt 68 is maintained under substantially constant tension by a belt tightener or tensioner generally designated 70, and illustrated in Figures 1 and 8. The belt tensioner comprises a rock frame 71 pivoted as at 72 on a frame-mounted bracket 73, an idler pulley 74 journaled at 75 at the rear end of the frame 71, and another idler pulley 76 journaled at 77 on the rock frame 71 in front of the rock frame pivot 72. The idler pulley 74 is positioned above and the idler pulley 76 is positioned below the upper stretch of the belt 68. A spring 78 interposed between the front end of the rock frame 71 and a fixed part 78^a on the machine frame urges the rock frame in a clockwise direction as viewed in Figure 1, causing the pulley 74 to press downwardly and the pulley 76 to press upwardly against the upper stretch of the belt 68, thereby maintaining the belt under substantially constant tension so that it will be driven by the pulley 67 at a substantially constant speed.

Variation of the snatch roll speed is effected by varying the speed of the pulley 69 and, in accordance with the invention, the pulley speed is varied by adjusting the width of the V groove in the pulley 69 so as to vary the effective diameter at which the belt 68 engages the pulley 69. To this end the pulley 69 is constructed and coordinated with the snatch roll 9 itself and with adjusting mechanism to be described, in a novel manner enabling the adjustments to be made effectively. The adjusting mechanism is so interrelated with the pulley 69, the snatch roll and other parts of the power mechanism as to require no substantial additional space and so as to enable adjustments to be made from the outside of the typewriter frame when the snatch roll is running, if so desired.

As shown in Figure 3, the snatch roll 9 is provided with journal portions or pins 79 and 80 secured respectively in bores 81 and 82 formed in the ends of the snatch roll. The pin 80 extends through the hub 83 of one section 84 of the pulley 69, and is free to slide or shift relatively axially with respect to the pulley section 84. The hub 83 is journaled in a bearing liner 85 carried by a cap 86 mounted in a fixed frame 75 wall 87. The bearing 85 is formed with a flange

or rim 88 which abuts against a mating shoulder in the cap 85 to hold the bearing against movement toward the right, as viewed in Figure 3. Fitted to the hub 83 after assembly of the parts is a flange or rim 89 which abuts the left-hand end of the bearing liner 85.

The pulley 69 includes another section 90 separated from the section 84 on a median plane and formed with a hub 91 which is fitted on a reduced part of the right-hand end of the snatch roll journal portion 80 as shown in Figures 2 and 3. The pulley section hub 91 is held tightly against a shoulder 92 on the journal portion 80 by means of a connecting plate 93, which fits on a flat part of the journal portion 80, and a securing screw 94. The connecting plate 93 is formed with a slot 95 which receives for sliding movement a pin 96 anchored as at 97 to the pulley section 84, the pin passing freely through a hole 98 in the pulley section 90. Thus the pulley sections 84 and 90 are relatively displaceable axially with respect to each other, but are constrained to rotate together by the connection provided by the pin 96. The pulley section 90 is fixed to the snatch roll 9 through the journal portion 80 of the snatch roll so as to rotate and also to shift axially with the snatch roll.

The journal portion 79 at the left end of the snatch roll 9 extends through a bearing 99 supported by a cap 100 mounted on another fixed frame wall 87 and having a sleeve 101 extending to the left of the associated wall 87. The journal portion 79 is free to rotate in and shift axially with respect to the bearing 99, and the outer end of the journal portion abuts an antifriction ball 102 received in a socket or seat 103 formed in the adjacent end of an adjusting screw 104 having threaded engagement with internal threads 105 formed in the cap sleeve 101. A spring 106, interposed between the left-hand end of the hub 83 of the pulley section 84 and the root of a counterbore 107 formed in the right end of the snatch roll 9, constantly urges the snatch roll 9 toward the left so that the journal portion 79 presses against and is backed up by the antifriction ball 102.

The adjusting screw 104 is rotatable in the sleeve 101 to convert its rotation to linear motion so as to shift the snatch roll 9 toward the right against the urge of the spring 106, thereby also shifting the pulley section 90 of the adjustable pulley 69 axially away from the companion pulley section 84 so as to decrease the effective diameter at which the pulley 69 is engaged by the V belt 68. Conversely, when the screw device 104 is backed off so as to retract the antifriction ball 102 the spring 106 acts in a follow-up manner so as to shift the snatch roll 9 toward the left and bring the pulley section 90 closer to the companion pulley section 84, thereby increasing the effective diameter at which the belt 68 engages the pulley 69.

The rotation of the screw 104 is facilitated by the provision of a knurled adjusting knob device 108 having a hub 109 fitted on a shank 110 of the screw 104, and secured to the shank by a set screw 111. The knob 108 is indexed or provided with scale markings 112 which can be read in connection with a pointer 113 which conveniently may be bent or pressed outwardly from the adjacent frame mask or cover portion 114. In order to limit the rotation of the knob 108 in a direction causing the screw 104 to move to the left, the frame mask portion 114 is formed with a stop projection 115 which is positioned to be

engaged by the set screw 111 when the latter has been moved to the left coincidental to leftward movement of the screw 104 to a predetermined limit position. Movement of the screw 104 in the opposite direction is limited by engagement of the right-hand end 116 of the knob hub 109 with the left-hand end 117 of the sleeve 101. Figure 3 shows the parts in full lines in intermediate positions of adjustment wherein the snatch roll 9 is so positioned that it may be moved either toward the right to occupy the position indicated in dotted lines, or toward the left.

If it is desired to make no carbon copies or only a minimum number of carbon copies when typing, the knob 108 is turned so as to bring the index "0" (zero) opposite the pointer 113, thus moving the ball 102 to the left until rotation of the knob is arrested by engagement of the set screw 111 with the stop projection 115. Movement of the ball 102 to the left will enable the spring 106 to move the snatch roll, the journal portion 80, and the pulley section 90 to the left so as to reduce the width of the V groove in the pulley 69 and increase the effective diameter at which the belt 68 engages the pulley. Inasmuch as the belt 68 is driven at a constant speed as explained previously, the increasing of the effective diameter of the pulley 69 effects a transmission ratio change, reducing the rotative speed of the snatch roll 9. When the snatch roll is rotating at a relatively low speed, the impulse delivered to the pawl 23 and the associated parts is relatively small so that the type bar 4 is driven to printing position at such speed as to produce a relatively light typing impact. If it should be desired to make a large number of carbon copies, say twenty, the knob 108 is turned in the opposite direction until the number "20" on the knob registers with the pointer 113. This will move the ball 102 toward the right so as to push the snatch roll and connected parts toward the right against the urge of the yielding spring 106. The parts thus moved toward the right include the pulley section 90, which is relatively separated from its companion section 84, thus increasing the width of the pulley groove and reducing the effective diameter at which the belt 68 engages the pulley 69. In this way a driving ratio change is effected, causing the snatch roll 9 to be driven at an increased speed so as to deliver increased impulses to the pawl 23 and operate the type bar 4 with greater force and more impact upon the work sheets. It is apparent that varying intermediate degrees of type bar impact may be obtained by setting the knob 108 so that the pointer 113 registers with appropriately selected scale indicia between "0" and "20" on the knob.

Figure 6 shows parts of a power driven carriage returning mechanism which is not claimed in the present application but which is closely associated with the power transmitting mechanism E and which therefore may be described briefly. Secured to the bracket 56 by screws 118 is an arbor 119 formed with a sleeve part 120 concentric with the shaft 61. The sleeve part 120 mounts a bearing bushing 121 on which is journaled a hub 122 of a winding drum 123 formed with a groove 124 which receives a draw band 125. The band 125 may be connected to the carriage B, for example as shown in copending application Serial No. 21,476 previously referred to. Secured to the shaft 61 by threads 126 is a clutch ring carrier disk 127 surrounded by a

flange 128 on the drum 123. A split clutch ring 129 is connected to the disk 127 at a point not shown, so as to have substantially semicircular or arcuate portions disposed within, but normally out of engagement with, the drum flange 128. The ring portions may be expanded to engage the flange 128 by moving a cone 130 axially to the left on the shaft 61 so as to spread clutch-engaging fingers 131 which operate through connections, not shown, to expand the ring 129. The cone 130 may be moved to the left through the medium of a fork 132 operatively connected to a collar 133 on the shaft 61 and being shiftable toward the left to press against an antifriction ball bearing assembly 134 which, in turn, presses against the cone 130. Key-controlled actuating mechanism of the general character disclosed in copending application 21,476 may be interposed between the fork 132 and the actuator and pawl mechanism shown in Figure 9 of the present application.

The mechanism disclosed embodies the invention in a preferred form, but it is intended that the disclosure be illustrative rather than definitive, the invention being defined in the claims.

I claim:

1. In a power operating mechanism for a typewriter or like machine, a rotatable toothed snatch roll; a typing member to be operated by said snatch roll; means for transmitting drive from said snatch roll to said typing member including an interponent having a contact part normally disengaged from said snatch roll but being engageable therewith by entrance into a tooth interspace thereof; operator controlled means for effecting such engagement of said interponent part with said snatch roll; an adjustable stop separate from said operator controlled means and said snatch roll; and another part on said interponent engageable with said stop for variably limiting the extent of entrance of said interponent contact part into a snatch roll tooth interspace, adjustment of said stop thereby variably determining the extent of driving of said interponent and said typing member by said snatch roll.

2. In a power operating mechanism for a typewriter or like machine, a rotatable toothed snatch roll; a typing member to be operated by said snatch roll; an actuator connected to said typing member and being normally disconnected from said snatch roll; a spring urged interponent movably mounted on said actuator and having a contact part normally disengaged from said snatch roll but being engageable therewith under spring urge by entrance into a tooth interspace thereof; operator controlled means normally restraining said interponent from engagement with said snatch roll but being operable for discontinuing its restraint to enable the spring urge to effect engagement of said interponent contact part with said snatch roll; an adjustable stop on said actuator; and another part on said interponent engageable with said stop for variably limiting spring-urged movement of said interponent relatively to said actuator, adjustment of said stop variably determining the extent to which said interponent contact part can be moved by spring urge into a snatch roll tooth interspace, and consequently variably determining the extent of driving of said interponent, said actuator, and said typing member by said snatch roll.

3. In a power operating mechanism for a typewriter or like machine, a rotatable toothed snatch roll; a typing member to be operated by said snatch roll; an actuator connected to said typing

member and being normally disconnected from said snatch roll; a spring urged interponent movably mounted on said actuator and having a contact part normally disengaged from said snatch roll but being engageable therewith under spring urge by entrance into a tooth interspace thereof; operator controlled means normally restraining said interponent from engagement with said snatch roll, but being operable for discontinuing its restraint to enable the spring urge to effect engagement of said interponent contact part with said snatch roll; a first stop element on said actuator; and a second stop element on said interponent engageable with said first stop element for limiting spring-urged movement of said interponent relatively to said actuator and thus limiting the extent of entrance of said interponent contact part into a snatch roll tooth interspace and determining the extent of driving of said interponent, said actuator, and said typing member by said snatch roll, one of said stop elements being bendable towards and away from the other of said stop elements for varying the limit of entrance of said interponent contact part into a snatch roll tooth interspace.

4. In a power operated typewriter or like machine, an instrumentality to be operated; a driving member; means journalling said driving member for rotation; means operatively connected to said instrumentality and being transiently connectible to said driving member for transmitting drive therefrom to said instrumentality; a V type groove pulley journalled for rotation at one end of and coaxially with said driving member and being drivingly connected thereto and divided medially of the groove to be constituted by two sections; means mounting one of said sections for axial displacement relative to the other of said sections for varying the width of said groove; an adjusting device mounted at the other end of and coaxial with said driving member; means for transmitting motion from said adjusting device axially through said driving member to said one of said sections; a motor; and a belt drivingly connecting said motor to said pulley.

5. In a power operated typewriter or like machine, an instrumentality to be operated; a driving member; means journalling said driving member for rotation; means operatively connected to said instrumentality and being transiently connectible to said driving member for transmitting drive therefrom to said instrumentality; a V type groove pulley journalled for rotation at one end of and coaxially with said driving member and being drivingly connected thereto and divided medially of the groove to be constituted by two sections; means mounting one of said sections for axial displacement relative to the other of said sections for varying the width of said groove; a rotatable adjusting device mounted at the other end of and coaxial with said driving member; means including a screw device for converting rotation of said adjusting device to linear motion and transmitting the linear motion through said driving member to said one of said sections; a motor; and a belt drivingly connecting said motor to said pulley.

6. In a power operated typewriter or like machine, an instrumentality to be operated; a driving member; means journalling said driving member for rotation; means operatively connected to said instrumentality and being transiently connectible to said driving member for transmitting drive therefrom to said instrumentality;

tality; a V type groove pulley journalled for rotation at one end of and coaxially with said driving member and being drivingly connected thereto and divided medially of the groove to be constituted by two sections; means mounting one of said sections for axial displacement relative to the other of said sections for varying the width of said groove; a spring urging said one of said sections axially in one direction with respect to the other of said sections; a rotatable adjusting device mounted at the other end of and coaxial with said driving member; means including a screw device for converting rotation of said adjusting device to linear motion and transmitting the linear motion through said driving member to said one of said sections for moving the latter axially in the opposite direction against the urge of said spring; a motor; and a belt drivingly connecting said motor to said pulley.

7. In a power operated typewriter or like machine, an instrumentality to be operated; a pair of axially aligned spaced bearings; a rotatable driving member having journal portions at its opposite ends mounted respectively in said bearings for both rotation and axial shifting; a V type groove pulley mounted on said member and comprising two mutually axially displaceable pulley sections, one of said sections being connected to said member for concurrent rotation therewith and being constrained against axial movement relatively to said member, the other of said sections being shiftable axially relatively to said member; a spring urging said driving member and said one of said pulley sections axially toward one end of said member; a fixed internally threaded sleeve axially aligned with the bearing adjacent said end of said member; adjusting means including a screw having threaded engagement with said sleeve and being rotatable for pushing said member and said one of said sections axially against the urge of said spring for varying the width of the pulley groove; a motor; and a belt driven by said motor and engaging the walls of the pulley groove for driving said pulley and said driving member.

8. In a power operated typewriter or like machine, an instrumentality to be operated; a pair of axially aligned spaced bearings; a rotatable driving member having journal portions at its opposite ends mounted respectively in said bearings for both rotation and axial shifting; a V type groove pulley mounted on said member and comprising two mutually axially displaceable pulley sections, one of said sections being connected to said member for concurrent rotation therewith and being constrained against axial movement relatively to said member, the other of said sections being shiftable axially relatively to said member; a spring urging said driving member and said one of said pulley sections axially toward one end of said member; a fixed internally threaded sleeve axially aligned with the bearing adjacent said end of said member; adjusting means including a screw having threaded engagement with said sleeve and having a seat in its end adjacent said one end of said member, and an anti-friction ball in said seat engaging said one end of said member, rotation of said screw in one direction effecting pushing of said ball, said driving member, and said one of said sections axially against the urge of said spring for

varying the width of the pulley groove; a motor; and a belt driven by said motor and engaging the walls of the pulley groove for driving said pulley and said driving member.

5 9. In a power operated typewriter or like machine, an instrumentality to be operated; a pair of axially aligned spaced bearings; a rotatable driving member having journal portions at its opposite ends mounted respectively in said bearings for both rotation and axial shifting; a V type groove pulley mounted on said member and comprising two mutually axially displaceable pulley sections, one of said sections being connected to said member for concurrent rotation therewith and being constrained against axial movement relatively to said member, the other of said sections being shiftable axially relatively to said member; a spring urging said driving member and said one of said pulley sections axially toward one end of said member; a fixed internally threaded sleeve axially aligned with the bearing adjacent said end of said member; and adjusting means including a screw having threaded engagement with said sleeve and being rotatable for pushing said member and said one of said sections axially against the urge of said spring for varying the width of the pulley groove, an adjusting knob, a set screw for securing said knob to said adjusting screw, and a fixed stop engageable by said set screw for limiting rotation of said knob and said adjusting screw in one direction.

10. In a power operated typewriter or like machine, an instrumentality to be operated; a driving member; means journalling said driving member for rotation; means operatively connected to said instrumentality and being transiently connectible to said driving member for transmitting drive therefrom to said instrumentality; a V type groove pulley journalled for rotation at one end of and coaxially with said driving member and being drivingly connected thereto and divided medially of the groove to be constituted by two sections; means mounting one of said sections for axial displacement relative to the other of said sections for varying the width of said groove; a manually rotatable, scale-marked adjusting device mounted at the other end of and coaxial with said driving member; means including a screw device for converting rotation of said adjusting device to linear motion and transmitting the linear motion through said driving member to said one of said sections; a motor; and a belt drivingly connecting said motor to said pulley.

HENRY J. HART.
